T-SQUARE SECURING MEANS

Harold Addison Chapin, San Jose, Calif.

Application September 15, 1949, Serial No. 115,915

3 Claims. (Cl. 33—80)

1

This invention relates to T-squares, and more particularly, to a T-square which is adapted to be attached to a drawing board or the like for use by draftsmen.

The main object of the invention is to provide a T-square embodying means whereby the same is readily held in place at a desired position, said means being operated by the user of the T-square to release same from the board whereby the same can be moved to various and desired positions.

Another object of the invention is to provide said T-square with a head, a board gripping member, and spring means operable to force the board-engaging member into contact therewith and thereby hold the T-square in desired positions.

The invention is illustrated in the accompanying drawings, in which:

Fig. 1 shows a top plan view of a drafting board and the T-square attached thereto;

Fig. 2 is a view in side elevation showing the T-square attached to the board;

Fig. 3 is a longitudinal sectional view through the center of the T-square;

Fig. 4 is a section on the line 4—4 of Fig. 1;

Fig. 5 is a sectional view on the line 5—5 of Fig. 3;

Fig. 6 is a top plan view of a portion of the head of the T-square with the knob and sheath removed;

Fig. 7 is a bottom view adjacent the end of the blade of the T-square showing the board clamping member and its connection to the operating rod; and

Fig. 8 is a section on the line 8—8 of Fig. 3.

Referring specifically to the drawings, in which like numerals indicate similar parts throughout the various views, a portion of a drafting board is indicated at 6 to which is attached the present invention, which comprises a T-square including a head 7, a blade portion 8, said blade portion comprising at its respective sides plastic straight edges 9 and 10, said straight edges being connected as by a web member 11, said web being bent to provide U-shaped portions 12 and 13 at its respective sides, said U-shaped portions rigidly gripping the straight edges 9 and 10 of the blade.

The web portion 11 has attached to its under side, as by welding or the like, a plate 14 which is bent downwardly as at 15 to form a recess between the web and the under surface thereof for a purpose to later be described.

The T-square is further provided with a housing, or sheath portion, 16 bent at its respective sides 17 to form a recess for accommodating a

plate 18. The sheath, or housing, 16 has attached thereto a knob 19 as by a screw 20 extending upwardly through the housing into the knob.

2 The plate 18, which is mounted within the housing 16, has attached to its outer end a bar, or head, 21 as by screws 22, said head having a groove 23 therein, said groove being adapted to receive one end of an operating rod 24, the operating rod extending longitudinally through the arch 15 formed by the plate 14 and being connected at its other end as by welding or the like at 25 to an angled board-engaging plate 26.

3 A tension spring 27 has its opposite legs 28 and 29 connected respectively within recesses formed in the head member 21 and the head member 7, whereby a spring tension is always exerted through the operating rod 24 to the board-engaging plate 26 to normally hold the same in engagement with the far side of the drafting board.

4 The T-square blade and its head are held in place as by a plurality of screws 30, said screws extending through the sheath 16 into engagement with the head 7. The plate 18 has longitudinal recesses, or guideways, 31 and 32, said guideways accommodating screws 30 and further limiting the inward and outward movement of the plate 18.

5 The blade of the T-square is longitudinally corrugated as at 33 and 34, which tends to strengthen the blade and thereby prevent the same from warping.

6 It will be noted that the operating rod 24 terminates short of the end of the blade 8 and that the under surface of the blade is provided with an arch-shaped guide member 35 to guide the member 26 when the same is moved by the operation of the rod 24.

7 It will be further noted that the board 6 is provided at one of its sides with an over-extending lip portion 36 which is adapted to receive the cut-out portion 37 of the head 7 when the same is in tight engagement with the edge of the board to thereby provide a better bearing surface for the sliding head.

8 In the operation of the device, the T-square is applied to the board at any desired position, and as will be seen, due to the tension of the spring 27 between the head 21 and the head 7, the operating rod 24 being attached to the board engaging angle member 26 normally tends to operate such board engaging angle member and thereby holds the T-square in a tight fit along the edge of the board, and thus the user of the T-square 55 is free to use both hands during the drafting op-

eration as he does not have to hold the T-square against the board.

When it is desired to move the T-square along the board, the operator grips the knob 19 between the thumb and forefinger of the left hand, whereupon he can manipulate the rod 24 through the head 21 as by the remaining fingers of his left hand to thereby compress the spring, move the operating rod 24 inwardly and thus release the clamping plate 26, whereupon the T-square can be readily moved to a new desired position. Then upon releasing of the head 21, the spring will move the head to the left, thereby moving the operating rod 24 and in consequence the clamping plate 26 against the far edge of the board to again lock the T-square in the new desired position.

It will readily be seen that this is a neat construction, all of the operating parts being substantially concealed and below the surface of the T-square and its arm, and, further, that the same can be readily and easily manipulated for moving the T-square when desired.

The draftsman using the device has both hands free for using his instruments, and, further, it eliminates the possibility of the T-square being accidentally moved with the result that inked lines are never accidentally blurred by the slipping of the T-square.

The invention is not intended to be limited to the exact construction shown, the disclosure being a preferred construction of the invention, the same being capable of various modifications within the scope of the following claims.

I claim:

1. A T-square having a head and a blade, said blade being corrugated longitudinally and provided at opposite sides with straight edges, an upstanding operating knob and a channel-shaped housing rigidly attached to the T-square head, an operating plate slidable in said housing, an operating head attached to the underside of said slideable plate, a rod connected to the operating head of the plate and extending longitudinally of the blade of the T-square, a board-engaging grip attached to the end of the rod adjacent the end of the blade, an arched plate connected to the under side of the T-square blade and enclosing and guiding said rod, a spring interposed between the T-square head and the head attached to the operating plate, said spring normally tending to engage the board-engaging grip with a drawing board to hold the T-square in position thereon.

2. A T-square having a head and a blade, a knob and a channel-shaped housing rigidly con-

nected to the T-square head, a slideable plate having oppositely disposed longitudinally extending recesses formed therein, said plate being movable within the housing, an operating head attached to the underside of said slideable plate, an operating rod connected to the head of the slideable plate and mounted beneath the upper surface of the T-square blade and movable thereunder, a board-engaging grip attached to the far end of the operating rod, a guide for said grip, a spring means interposed between the T-square head and the head carrying the operating rod, said spring normally urging the grip to engagement with a drafting board.

3. A T-square securing device comprising a drawing board and a T-square, said T-square having a head and a blade, an upstanding operating knob mounted on the T-square head, a channel-shaped guide housing connected to the operating knob, an operating plate slideable in the guide housing, a depending operating head mounted at the outer end of the operating plate and laterally spaced with respect to the operating knob, a rod connected to the operating head of the plate and extending longitudinally of the blade of the T-square, the blade having an intermediate flat portion and a plate secured to the intermediate flat portion of the blade and having a medial depression therein, the rod lying in the medial depression beneath the blade portion, and a board-engaging grip attached to the end of the rod adjacent the end of the blade, and a spring having one end attached to the T-square head and the other end attached to the head of the operating plate, said spring normally tending to engage the board-engaging grip with the drawing board to hold the T-square in position thereon.
